UNITED STATES PATENT OFFICE

2,669,985

COMBINATION GAS AND OIL RANGE

Domenick Saponara, Spring City, Pa., assignor to
 The Floyd Wells Company, Royersford, Pa., a
 corporation of Pennsylvania

Application November 16, 1948, Serial No. 60,374

1. Claim. (Cl. 126—1)

The object of this invention is to devise a novel range of the dual fuel type, and while the range is primarily designed to use oil or gas as a fuel, it is practical to substitute electric elements for the gas so that the range can use oil and electricity.

A further object of the invention is to design a range wherein the oven bottom is heated directly by the oil burner, and the hot gases pass up through flues at each side of the oven compartment and leave through an uncontrolled flue outlet. In the conventional range, the oven is heated by a burner located in a compartment adjacent to one side of the oven, and the gases are drawn across the top of the oven, down one side and finally underneath the oven to pass to the chimney or outlet for the products of combustion. By direct bottom heating, a more effective circulation of air in the oven is obtained, and food may be cooked on oven racks rather than on the oven bottom, which doubles the capacity of the oven since two racks may be used, whereas in the conventional range only the oven bottom is available.

A further object of the invention is to devise an oven and heating arrangement which does not require a fairly strong chimney draft and which will vent itself, since the only function of the chimney is to carry off the products of combustion. In the present type of ranges, a chimney draft is required to draw the products of combustion around the oven, and, if there is a leak in some part of the range adjacent to the flue, infiltration of heated air from the oven into the flue causes inefficiency or may cause cold air to be drawn into the oven with the result that there is difficulty in heating up the oven. In the present invention, as the oven heats, a natural draft is set up in the oven compartment causing circulation of air from the bottom to the top of the oven. A small part of this air will leave through the outlet and be replaced by air at room temperature entering through the air intake. This latter air, however, will be heated by the oil burner and passes up into the oven compartment as heated air.

A further object of the invention is to devise a novel construction which will eliminate the necessity of employing a damper at the outlet as has heretofore been deemed necessary to permit the oven to heat when using oil as a fuel. A certain amount of air is permitted to escape and the incoming air which replaces it is immediately heated by the burner.

With the foregoing and other objects in view 55 Heat for top cooking with oil as a fuel is sup-

as will hereinafter clearly appear, my invention comprehends a novel range of the dual fuel type.

A further object of the invention is to devise a novel construction and arrangement of an oven and its intake and outlet, and novel means to effect the heating of the oven bottom.

For the purpose of illustrating the invention, I have shown in the accompanying drawings a preferred embodiment of it which I have found in practice to give satisfactory and reliable results. It is, however, to be understood that the various instrumentalities of which the invention consists can be variously arranged and organized, and the invention is not limited to the exact arrangement and organization of these instrumentalities as herein set forth.

Figure 1 is a top plan view of a range for dual fuels, embodying my invention.

Figure 2 is a sectional elevation of the range.

Figure 3 is a section on line 3—3 of Figure 2. Similar numerals of reference indicate corresponding parts.

Referring to the drawings:

The range has an outer casing 1, within which 25 is a compartment 2 to receive an oil tank 3.

Oven heating by oil

A conduit 4 leads from the oil tank 3 to an oven oil burner 5, mounted on a support 6. A partition 7 has a central opening 8 into which the upper end of the oil burner 5 extends with a clearance. The products of combustion from the oil burner 5 pass to a flue 9 beneath the bottom 10 of an oven 11, then through side flues 12 and 13 to a flue outlet 14 leading to a chimney. The bottom of the oven is thus directly heated by the oil burner and the products of combustion pass from the side flue 13 over the top of the oven.

As the oven heats up, a natural draft is set up 40 in the oven compartment causing circulation from the bottom of the oven to its top. Air at room temperature enters at air intake opening 15 and leaves the oven compartment at an outlet 16. This air entering at intake opening 15 is 45 heated by the oil burner 5 and passes up into the oven compartment as warm air.

The air intake is formed by a channel having its sides resting on the oven bottom and having its top apertured. The space within the channel 50 forms an air heating chamber for air flowing freely into said chamber and circulating in the oven to pass out through the outlet 16.

Top cooking by oil

plied by an oil burner 17 fed by a conduit 18 leading from an oil tank 19 supported on a bracket 20 at the rear of the range. The oil burner 17 is in a compartment 21 above the oil tank 3 and such compartment has an insulated bottom 22. The products of combustion from the oil burner 17 pass beneath the top cooking surface 23, provided with removable pot hole covers 24, and to the flue outlet 14. A limited amount of top cooking is provided by the products of combustion passing from the oil burner 5 to the flue outlet 14.

Top cooking with gas or electricity

For top cooking with gas or electricity, a conventional arrangement of four units 25 is shown in the upper right hand compartment 26, see Figure 2.

Oven heating with gas

For heating the oven with gas, a gas burner 27 is located beneath a baffle 28 forming an oven bottom. Air for combustion enters at air intake opening 15 and the products of combustion leave the oven compartment at the flue outlet 16.

Heat for broiling

For broiling, instead of using the oven for baking, a separate broiling compartment is provided so that the capacity of the range is increased since both ovens can be used at the same time. A broiler compartment 29 is provided at one side of the baking oven and has its top and sides insulated, see Figure 2. The compartment 29 is provided with a broiler burner 30 and a flue outlet 31. A broiler pan 32 is selectively positioned on guides 33.

The range has conventional insulated doors 34, and its casing is supported on chambered base members 35 having levelling devices 36.

The oil burners may be single or double burners or multiple burners.

It will now be apparent that the oven is heated by oil directly from the bottom.

Heat for top cooking is supplied by a second burner in a separate compartment, although a portion of the heat from the oven burner can be utilized for a limited amount of top cooking.

By heating the oven with oil from the bottom, circulation is set up in the oven which permits food to be cooked on two racks, and it is not necessary to cook directly on the oven bottom.

The foregoing permits the design of the oven when operating with gas to be identical to that of a standard range oven for gas, whereas the conventional combination range requires a makeshift arrangement of the oven burner and various baffles which are usually removed when operating with oil.

No substantial or specific degree of chimney draft is required for the operation of the range. The only purpose which the chimney serves is to carry off the spent products of combustion from the oil burners.

The design aids in manufacturing since the joints in the flues need not necessarily be tight. If the joints are not tight, the performance of the range is not affected to any substantial degree.

The arrangement of the parts including the broiler unit is advantageous both from an operating and a construction viewpoint.

A damper is not necessary in the oven outlet. In prior ranges of this type, a damper has been deemed necessary to permit the oven to heat when using oil as a fuel. In this invention, a certain amount of air is permitted to escape and the incoming air which replaces it is immediately heated by the oven burner.

The present design as illustrated permits substantial savings in manufacturing costs.

The oven and the broiling compartment can be used at the same time thus doubling the capacity of the range.

The oven is spaced from the compartments above the partition 7 to contribute to form the side flues 12 and 13, and the oven is spaced from the top of the range to form a top flue leading to the outlet 14. The flue 13 leads to the top flue, and the inner wall of the oil burner compartment 21 terminates a desired distance above the oil burner 17 for top cooking.

Having thus described my invention, what I claim as new and desire to secure by Letters Patent is:

In a combination range, a casing having a top cooking surface, a burner compartment beneath said top surface at one side of the range and adapted to contain a burner, a broiler compartment at the opposite side of the range and adapted to contain a burner, an oven having side walls spaced from walls of said compartments to form side flues and spaced from said top surface to form a top flue in communication with the side flues, said casing having an uncontrolled flue outlet above the top oven wall and communicating with the burner compartment, side flues and top flue, a partition below the oven contributing with it to form a bottom flue communicating with the side flues and provided with a central opening, an oil burner having a clearance in said opening for air admission and for applying heat centrally to the oven bottom, an apertured channel forming an air heating chamber and an air intake within the oven and extending laterally across the bottom above the oil burner, a baffle fixed in the oven above the air intake, and said oven adapted to accommodate a gas burner between the baffle and the air intake.

DOMENICK SAPONARA.
